United States Patent Office

Des. 220,029
Patented Mar. 2, 1971

220,029

BOTTLE

Roland E. Johnson, Cincinnati, Ohio, assignor to The Procter & Gamble Company, Cincinnati, Ohio

Filed Sept. 25, 1969, Ser. No. 19,296

Term of patent 14 years

Int. Cl. D9—01

U.S. Cl. D9—116

FIG. 2

FIG. 1

Fig. 3

Fig. 4

FIG. 1 is a front elevational view of a bottle showing my new design, a part being broken away to show the bottom configuration;

FIG. 2 is a top plan view of the same;

FIG. 3 is a side elevational view of the same; and

FIG. 4 is a bottom plan view of the same.

The sides not shown are the same as the sides shown.

I claim:

The ornamental design for a bottle, as shown and described.
